CLAIM

The ornamental design for a beverage container, as shown and described.

DESCRIPTION

FIG. 1 is an isometric view of a beverage container showing the design.

FIG. 2 is a side elevation view of the beverage container of FIG. 1.

FIG. 3 is another side elevation view of the beverage container of FIG. 1.

FIG. 4 is another side elevation view of the beverage container of FIG. 1.

FIG. 5 is another side elevation view of the beverage container of FIG. 1.

FIG. 6 is a top plan view of the beverage container of FIG. 1.

FIG. 7 is a bottom plan view of the beverage container of FIG. 1.

FIG. 8 is another isometric view of the beverage container of FIG. 1.

FIG. 9 is an isometric view of a beverage container showing the design.

FIG. 10 is a side elevation view of the beverage container of FIG. 9.

FIG. 11 is another side elevation view of the beverage container of FIG. 9.

FIG. 12 is another side elevation view of the beverage container of FIG. 9.

FIG. 13 is another side elevation view of the beverage container of FIG. 9.

FIG. 14 is a top plan view of the beverage container of FIG. 9.

FIG. 15 is a bottom plan view of the beverage container of FIG. 9; and,

FIG. 16 is another isometric view of the beverage container of FIG. 9.

The dashed lines shown in the drawings illustrate portions of the beverage container that form no part of the claimed design.

1 Claim, 14 Drawing Sheets
